UNITED STATES PATENT OFFICE.

WILLIAM K. WEBB AND EDWARD B. ANDRESS, OF WILKINSBURG,
PENNSYLVANIA.

DESIGN FOR A SHOESTRING-FASTENER.

SPECIFICATION forming part of Design No. 26,635, dated February 16, 1897.

Application filed December 21, 1896. Serial No. 616,551. Term of patent 14 years.

To all whom it may concern:

Be it known that we, WILLIAM K. WEBB and EDWARD B. ANDRESS, citizens of the United States of America, residing at Wilkinsburg, in the county of Allegheny and State of Pennsylvania, have invented a certain new and original Design in Shoestring-Fasteners, of which the following is a specification, reference being had therein to the accompanying drawing.

This invention relates to a certain new and original design in shoestring-fasteners, and in describing the invention in detail reference is had to the accompanying drawing, forming a part of this specification, like letters of reference indicating similar parts throughout the view, which is a perspective view of our design.

The principal feature of our design is the

plate *a*, having beveled corners *bb*, said plate being bent or doubled to form an upper plate *c*, the two plates thus formed constituting a hook, said upper plate being slightly curved, with the lowest point of depression in close proximity to the plate *a*. Projecting barbs *dd* are formed integral with the plate *a* and project downwardly therefrom.

Having fully described the invention, what we claim is—

The design for a shoestring-fastener, as herein shown and described.

In testimony whereof we affix our signatures in presence of two witnesses.

WILLIAM K. WEBB.

EDWARD B. ANDRESS.
